UNITED STATES PATENT OFFICE.

HENRY B. JOY, OF DETROIT, MICHIGAN, ASSIGNOR TO PACKARD MOTOR CAR COMPANY, OF DETROIT, MICHIGAN, A CORPORATION OF MICHIGAN.

DESIGN FOR AN AUTOMOBILE RADIATOR-FILLER CAP.

42,139.

Specification for Design.

Patented Feb. 6, 1912.

Application filed October 27, 1911. Serial No. 657,198. Term of patent 7 years.

To all whom it may concern:

Be it known that I, HENRY B. JOY, a citizen of the United States, residing at Detroit, in the county of Wayne and State of Michigan, have invented a new, original, and ornamental Design for an Automobile Radiator-Filler Cap, of which the following is a specification, reference being had to the accompanying drawing, forming part thereof.

In the accompanying drawing: Figure 1

is a side elevation of the cap; Fig. 2 is a plan view; Fig. 3 is a rear elevation; and Fig. 4 is a front elevation.

I claim:

The ornamental design for an automobile radiator filler cap, as shown.

HENRY B. JOY.
